3 Claims

ABSTRACT OF THE DISCLOSURE

This disclosure teaches that a new class of compounds, the 4-phenylbicyclo[2.2.2]octane and oct-2-ene-1-carbinols and carboxaldehydes are pharmaceutically useful as antifertility agents.

Compounds within the scope of this invention can be formulated into injectible, oral or rectal dosage forms and when administered by the appropriate route are surprisingly effective to prevent pregnancy in animals.

BACKGROUND OF THE INVENTION

This invention relates to a novel class of compounds, the 4-phenylbicyclo[2.2.2]octane and oct-2-ene-1-carbinols and carboxaldehydes. We have further discovered that this class of compounds can be used as antifertility agents in animals to prevent pregnancy.

This activity for the compounds of our invention is all the more startling when these compounds are compared in structure to contraceptive agents presently known to the medical art.

There are, at present, antifertility agents known to the medical arts. The agents which are known to be most effective for preventing pregnancy are estrogens and progestins.

Presently, the most widely accepted of these pharmaceutical agents are mixtures of steroid estrogens and progestins.

We have discovered that 4-phenylbicyclo[2.2.2]octane and oct-2-ene-1-carbinols and carboxaldehydes can be used in an entirely different manner to prevent pregnancy. Whereas the estrogen-progestin mixtures now most widely used must be taken for relatively long periods in anticipation of coitus, the compounds of this invention can be administered after coitus to prevent pregnancy. Although the exact mechanism of action is not well understood, animals indicate that, probably nidation is in some manner prevented.

Therefore, in addition to the striking structural difference of the compounds of this invention over known contraceptive agents, it also appears that the compounds of this invention exhibit a mechanism of action that materially differs from presently employed contraceptive drugs.

This new mechanism of action has numerous practical advantages such as ease of use, elimination of protracted periods of administration, elimination of a scheduled regimen of medication, and the avoidance of a continual state of pseudopregnancy, which is responsible for many side effects.

SUMMARY OF THE INVENTION

In summary, our invention relates to 4-phenylbicyclo[2.2.2]octane and oct-2-ene-1-carbinols and carboxaldehydes and their use as antifertility agents.

More particularly, the compounds of my invention are

the 4-phenylbicyclo[2.2.2]octane and oct-2-ene-1-carbinols and carboxaldehydes of the following formula:

where

A is a single bond or a double bond;

10 R₁ can be H, —OH, —OCH₃, —OC₂H₅, —OC₃H₇, —OC₄H₉ or

15 wherein R is an alkyl of from one through twelve carbons; and

R₂ can be —CHO or —CH₂OR₃, wherein R₃ can be hydrogen, an ester-forming monobasic acid radical such as acetyl, propionyl or an ester-forming dibasic acid radical, preferably forming hemi-esters such as hemisuccinyl, hemiglutaryl or hemiadipyl.

Of the above compounds wherein R₁ is

25 those compounds are preferred wherein R is an alkyl of one through four carbons.

DESCRIPTION OF THE INVENTION

30 The prefix "phenyl" as used in the general nomenclature for the compounds of this invention throughout this specification means phenyl group or substituted phenyl group. In those compounds in which the phenyl group attached to the bicyclooctane cage is substituted these substituents are para to the position at which the phenyl is attached to the cage structure. Further, the substituents include H, OH, OCH₃, OC₂H₅ and alkyl carboxylic acid esters of the paraphenol.

35 It is to be also understood that the term carbinols as used herein to describe the compounds of this invention is employed as a generic term which includes the carbinols, as such, and ester derivatives of these carbinols. The intermediate thus formed is cyclized to a pyrone by

40 treatment with anhydrous hydrogenchloride.

45 The alcohols of this invention are conveniently prepared by refluxing a mixture of the appropriate phenyl bicyclo[2.2.2]octane or oct-2-ene compound, a reducing agent and glyme under a nitrogen atmosphere until reaction is complete. After the mixture is cooled, water is cautiously added to the system to decompose the reducing agent. The water is evaporated and the residue dissolved in a mixture of water and an inert organic solvent. The organic layer is then separated from the mixture, dried and evaporated to give the desired phenylbicyclo[2.2.2]octane, or oct-2-ene-1-methanol.

50 In the above description, phenylbicyclo[2.2.2]octane or oct-2-ene compound is used to represent generically 4-phenyl and substituted 4-phenylbicyclo[2.2.2]octane-1-carboxylic acid, 4-phenyl and substituted 4-phenylbicyclo[2.2.2]octane-1-carboxylic acid lower alkyl ester, 4-phenyl and substituted 4-phenylbicyclo[2.2.2]oct-2-ene-1-carboxylic acid and 4-phenyl and substituted 4-phenylbicyclo[2.2.2]oct-2-ene-1-carboxylic acid lower alkyl ester.

55 A preferred reducing agent to be used in a reaction such as the one described above is lithium aluminum hydride.

60 A preferred solvent for use in the above reaction, glyme, is anhydrous ethylene glycol dimethyl ether. If desired, other readily available suitable solvents can be substituted for glyme in the above described reaction.

3

The 4-phenylbicyclo[2.2.2]octane and oct-2-ene-1-carboxaldehydes of this invention can be prepared by dissolving the desired 4-phenylbicyclo[2.2.2]octane or oct-2-ene-1-carboxylic acid and lithium metal in methylamine. Ethyl alcohol is then slowly added to this solution and the liquid is evaporated. The residue is dissolved in a quantity of water sufficient to cause solvation and the resultant solution is acidified and stirred, and the resulting precipitate is collected and dried. This precipitate is then dissolved in chloroform. The chloroform extract is chromatographed on silicic acid with chloroform as the eluent. The 4-phenylbicyclo[2.2.2]octane or oct-2-ene-1-carboxaldehyde fraction is collected and purified.

This invention will be better understood by reference to the following illustrated examples.

EXAMPLE 1

A mixture of 240 parts of acetophenone and 432 parts of diethyl ethoxymethylenemalonate is dropped into a flask containing a solution of 50.6 parts of sodium metal

5 5 10 15 20 25 30 35 40 45 50 55 60 65 70 75 80 85 90 95 100

A mixture of 0.03 mole of 4-phenylbicyclo[2.2.2]octane-1-carboxylic acid methyl ester, 0.1 mole lithium aluminum hydride, and 150 ml. of anhydrous ethylene glycol dimethyl ether (glyme) is refluxed under a nitrogen atmosphere for 4 hours. The mixture is cooled and water is cautiously added until the gray lithium aluminum hydride is converted to a white product. The precipitate is filtered off and is washed with glyme. The filtrate is evaporated and the residue is dissolved in a mixture of benzene and water. The benzene extract is dried with anhydrous $MgSO_4$ and is evaporated to give 4-phenylbicyclo[2.2.2]octane-1-methanol, M.P. 78.5-79.6° C., which can be recrystallized from methylcyclohexane.

4
EXAMPLE 2

The procedure of Example 2 is repeated substituting an equivalent amount of the indicated starting material for the 4-phenylbicyclo[2.2.2]octane-1-carboxylic acid methyl ester of Example 2 to obtain the indicated alcohol.

EXAMPLES 3-6

Starting material	Alcohol
Example:	
3..... 4-(p-methoxyphenyl)bicyclo[2.2.2]octane-1-carboxylic acid.	4-(p-methoxyphenyl)bicyclo[2.2.2]octane-1-methanol, M.P. 127-128° C.
4..... 4-(p-methoxyphenyl)bicyclo[2.2.2]octane-1-carboxylic acid ethyl ester.	4-(p-methoxyphenyl)bicyclo[2.2.2]octane-1-methanol, M.P. 127-128° C.
5..... 4-(p-ethoxyphenyl)bicyclo[2.2.2]oct-2-ene-1-carboxylic acid ethyl ester.	4-(p-ethoxyphenyl)bicyclo[2.2.2]oct-2-ene-1-methanol.
6..... 4-(p-hydroxyphenyl)bicyclo[2.2.2]octane-1-carboxylic acid.	4-(p-hydroxyphenyl)bicyclo[2.2.2]octane-1-methanol, M.P. 202-204° C.

in 2000 parts of absolute alcohol under a nitrogen atmosphere. The mixture is refluxed for 2 hours with stirring and is allowed to cool. About 1000 to 1500 parts of alcohol is removed by evaporation at reduced pressure, and sufficient ether is added to form a granular or powdery yellow precipitate. The precipitate is filtered off, washed with ether, and dried.

The crude yellow precipitate is added to 692 parts of anhydrous hydrogen fluoride at -60 to -70° C. The mixture is allowed to warm to room temperature and the excess hydrogen fluoride is then evaporated. Dichloromethane and water are added to the residue. The dichloromethane extract is washed with dilute $NaHCO_3$ solution, dried with anhydrous $MgSO_4$, and then evaporated. The residue is triturated with ethyl acetate to give the corresponding 3-carboethoxy-6-phenyl-2-pyrone, M.P. 107-109° C.

35 40 45 50 55 60 65 70 75 80 85 90 95 100

To a solution of 2.46 g. of 4-(p-methoxyphenyl)bicyclo[2.2.2]octane-1-methanol in 50 ml. of dry pyridine is added 5 ml. of acetic anhydride. The solution is allowed to stand for 16 hours. Then 5 ml. of H_2O is added, and the solution is allowed to stand for 4 hours. The solution is poured into a mixture of 200 g. of ice and 200 ml. of 6 N HCl. When the ice is melted, the precipitate is filtered off, is washed thoroughly with water, and is dried to give 4-(p-methoxyphenyl)bicyclo[2.2.2]octane-1-methanol acetate ester. Recrystallization of the ester from alcohol gives crystals, M.P. 105-106° C.

EXAMPLES 8-14

The procedure of Example 7 is repeated using the indicated starting alcohol and acid chloride or acid anhydride to give the indicated product.

Alcohol	Acid chloride or anhydride	Product
Example:		
8..... 4-phenylbicyclo[2.2.2]octane-1-methanol.	Acetic anhydride.....	4-phenylbicyclo[2.2.2]octane-1-methanol acetic acid ester.
9..... 4-(p-ethoxyphenyl)bicyclo[2.2.2]octane-1-methanol.	Dodecanoyl chloride.....	4-(p-ethoxyphenyl)bicyclo[2.2.2]octane-1-methanol dodecanoic acid ester.
10..... 4-(p-methoxyphenyl)bicyclo[2.2.2]oct-2-ene-1-methanol.	Succinic anhydride.....	4-(p-methoxyphenyl)bicyclo[2.2.2]oct-2-ene-1-methanol succinic acid mono-ester.
11..... 4-(p-methoxyphenyl)bicyclo[2.2.2]octane-1-methanol.	Adipyl chloride.....	4-(p-methoxyphenyl)bicyclo[2.2.2]octane-1-methanol adipic acid mono-ester.
12..... 4-(p-hydroxyphenyl)bicyclo[2.2.2]octane-1-methanol.	Acetic anhydride.....	4-(p-acetoxyphenyl)bicyclo[2.2.2]octane-1-methanol acetic acid ester.
13..... do.	Propionyl chloride.....	4-(p-propionyloxyphenyl)bicyclo[2.2.2]octane-1-methanol propionic acid ester.
14..... 4-(p-hydroxyphenyl)bicyclo[2.2.2]oct-2-ene-1-methanol.	Isobutyryl chloride.....	4-(p-isobutyroxyphenyl)bicyclo[2.2.2]oct-2-ene-1-methanol isobutyric acid ester.

The 3-carboethoxy-6-phenyl-2-pyrone (0.2 mole) is dissolved in 200 ml. of benzene and heated at 200° C. with 1000 atmospheres of ethylene for 16 hours in a suitable pressure vessel. The mixture is cooled. The benzene is evaporated and the residue is 4-phenylbicyclo[2.2.2]oct-2-ene-1-carboxylic acid ethyl ester, B.P. 192° C. at 12 mm./Hg.

The procedure of Example 1 can be repeated but substituting an appropriately substituted acetophenone for the acetophenone of Example 1 to obtain the desired 4-arylbicyclo[2.2.2]octane or oct-2-ene-1-carboxylic acid ester.

65 70 75 80 85 90 95 100

Acylation at the phenolic hydroxyl can be accomplished in the following manner.

EXAMPLE 15

A solution of 2.46 g. of 4-(p-hydroxyphenyl)bicyclo[2.2.2]octane-1-methanol in 50 ml. of pyridine is treated with 0.10 mole of acetic anhydride according to the procedure of Example 7, to give 4-(p-acetoxyphenyl)bicyclo[2.2.2]octane-1-methanol.

EXAMPLE 16

75 80 85 90 95 100

A solution of 2.46 g. of 4-(p-hydroxyphenyl)bicyclo[2.2.2]octane-1-methanol in 50 ml. of pyridine is treated

with 0.10 mole of propionyl chloride according to the procedure of Example 7, to give 4-(p-propionoxyphenyl)bicyclo[2.2.2]octane-1-methanol.

EXAMPLE 17

A solution of 3.16 g. of 4-(p-acetoxyphenyl)bicyclo[2.2.2]octane-1-methanol acetic acid ester and 1.38 g. of potassium carbonate in 100 ml. of 90% ethanol is refluxed for 16 hours. The resulting solution is cooled, poured into ice-water, and acidified with hydrochloric acid. The precipitate is filtered off, is washed with water, and is dried to give 4-(p-hydroxyphenyl)bicyclo[2.2.2]octane-1-methanol acetic acid ester.

EXAMPLE 18

To a solution of 12.9 g. of 4-(p-methoxyphenyl)bicyclo[2.2.2]oct-2-ene-1-carboxylic acid in 300 ml. of methylamine is added 3 g. of lithium metal. When the lithium is dissolved, 100 ml. of alcohol is dropped into the solution. The solution is evaporated. The residue is dissolved in 250 ml. of water, and then acidified with 150 ml. of 6 N HCl. The mixture is stirred for one hour. The precipitate is filtered off, washed with water, and dried. The residue is triturated with chloroform, and the extract is chromatographed on silicic acid with chloroform as the eluant. A fraction is obtained whose IR [2.9 μ (OH), 3.7 μ (aldehyde C-H), 5.89 (aldehyde C=O)] and N.M.R. [(CDCl₃, 0.12 τ (1H, singlet—aldehyde C-H), 2.92 τ (4H, quadruplet J~15 c./s.—para-disubstituted benzene), 3.45 τ (2H, doublet J~1 c./s.—olefinic protons), 4.20 τ (1H, singlet—phenolic OH), 8.00—8.53 τ (8H—aliphatic protons)] spectra show it to be 4-(p-hydroxyphenyl)bicyclo[2.2.2]oct-2-ene-1-carboxaldehyde. Recrystallization from xylene gives crystals, M.P. 154—155° C.

The procedure of Example 18 can be repeated substituting 4-(p-methoxyphenyl)bicyclo[2.2.2]octane-1-carboxylic acid for the 4-(p-methoxyphenyl)bicyclo[2.2.2]oct-2-ene-1-carboxylic acid of Example 18 to give as the product 4-(p-hydroxyphenyl)bicyclo[2.2.2]octane-1-carboxaldehyde.

EXAMPLE 19

A solution of 0.010 mole of 4-(p-hydroxyphenyl)bicyclo[2.2.2]octane-1-carboxaldehyde, 0.020 mole of sodium methoxide, and 0.020 mole of dimethyl sulfate in 50 ml. of methanol is refluxed for 16 hours. The solution is cooled and then poured into 400 ml. of 3% aqueous NaOH. The resultant precipitate is filtered off, washed with water, and dried to give 4-(p-methoxyphenyl)bicyclo[2.2.2]octane-1-carboxaldehyde.

EXAMPLE 20

A solution of 0.010 mole of 4-(p-hydroxyphenyl)bicyclo[2.2.2]oct-2-ene-1-carboxaldehyde, 0.020 mole of sodium methoxide, and 0.020 mole of diethyl sulfate in 50 ml. of methanol is refluxed for 16 hours. The solution is cooled and then poured into 400 ml. of 3% aqueous NaOH. The resultant precipitate is filtered off, washed with water and dried to give 4-(p-ethoxyphenyl)bicyclo[2.2.2]octane-1-carboxaldehyde.

The compounds of this invention can be administered to prevent pregnancy according to the method of this invention by any suitable means. For example, administration can be parenterally, that is subcutaneously, intramuscularly or intraperitoneally. Alternatively administration can be by the oral or rectal route.

In most animals these compounds are effective when given in a single dose prior to estimated time of implantation of the fertilized egg. Alternatively, these compounds can be administered in divided doses for from two to six days after mating with equivalent effectiveness if desired in place of the single dose. Therefore, these compounds can be administered in single or divided doses for from 0 to 15 days after coitus.

It is preferred that these compounds be administered after coitus, but before estimated time of implantation of the fertilized egg in the uterus.

The dosage administered will be dependent upon age, health and weight of the recipient and also upon the frequency of administrations. Generally, from 0.001 to 50 mg./kg./day of active ingredient for one or more days is effective to obtain the desired result.

A dosage of from 0.005 to 10 mg./kg./day is preferred with the most preferred dosage being in the range of from 0.01 to 5 mg./kg./day.

These compounds have shown outstanding inhibition of pregnancy in rats as will be seen from the following example. Therefore, the method of this invention can be used in addition to, or as a replacement for presently known rodent control methods.

EXAMPLE 23

Immature rats are induced into precocious puberty with a single dose of pregnant mares' serum gonadotropin and then are mated with normal males. A suspension of 4-(p-methoxyphenyl)bicyclo[2.2.2]octane-1-methanol acetic acid ester in sesame oil is administered orally daily for six days starting on the day of finding sperm or a vaginal plug.

One week after mating, the animals are killed and their uteri are examined for implantation sites. If any are found, the animal is considered pregnant. Control animals have a mean of eight implantation sites.

The dose at which fifty percent of the animals show no evidence of pregnancy, the ED₅₀, is calculated to be 0.31 mg./kg./day.

The test of Example 23 is repeated substituting 4-(p-methoxyphenyl)bicyclo[2.2.2]octane-1-methanol for the compound used in the above test. The ED₅₀ is found to be within a range of doses of from 0.31—1.24 mg./kg./day.

The test of Example 23 is again repeated substituting 4-(p-hydroxyphenyl)bicyclo[2.2.2]oct-2-ene-1-carboxaldehyde for the compound used in the above test. The ED₅₀ is found to be within a range of doses of from 0.31—1.24 mg./kg./day.

The method of administering a single dose of a compound of this invention is also demonstrated. The above test procedure is again repeated except that the compound of this invention is administered in a single oral dose

	Hydroxy compound	Acid anhydride or chloride	Ester
Example:			
21	4-(p-hydroxyphenyl)bicyclo[2.2.2]octane-1-carboxaldehyde.	Acetic anhydride	4-(p-acetoxyphenyl)-bicyclo[2.2.2]octane-1-carboxaldehyde.
22	4-(p-hydroxyphenyl)bicyclo[2.2.2]oct-2-ene-1-carboxaldehyde.	Propionyl chloride	4-(p-propionoxyphenyl)-bicyclo[2.2.2]octane-1-carboxaldehyde.

EXAMPLES 21 AND 22

The procedure of Example 7 is repeated substituting the indicated hydroxy compound for the 4-(p-methoxyphenyl)bicyclo[2.2.2]octane-1-methanol and indicated acid anhydride or chloride for the acetic anhydride of Example 7 to obtain the indicated ester.

to female rats on the third day, approximately fifty-three hours after mating.

When the compound administered in this fashion is 4-(p-methoxyphenyl)bicyclo[2.2.2]octane-1-methanol the ED₅₀ is calculated as 0.90 mg./kg./day.

The compounds of this invention can also be employed with equally satisfactory results to prevent pregnancy

$-\text{CHO}$, and $-\text{CH}_2\text{OR}_3$, wherein R_3 is selected from the group consisting of hydrogen,

hemisuccinyl, hemiglutaryl and hemiadipyl.

2. A compound of claim 1 which is a member of the group consisting of 4 - (p - methoxyphenyl)bicyclo[2.2.2]octane - 1 - methanol, 4 - (p - hydroxyphenyl)bicyclo[2.2.2]octane - 1 - methanol, 4 - phenylbicyclo[2.2.2]octane - 1 - methanol, 4 - (p - methoxyphenyl)bicyclo[2.2.2]octane - 1 - octane - 1 - methanol acetic acid ester, 4 - (p - hydroxyphenyl)bicyclo[2.2.2]octane - 1 - carboxaldehyde and 4 - (p - methoxyphenyl)bicyclo[2.2.2]octane - 1 - carboxaldehyde.

3. A compound of claim 1 which is 4-(p-methoxyphenyl)bicyclo[2.2.2]octane-1-methanol.
